US00D345703S

United States Patent [19]

Cervas

[11] Patent Number: Des. 345,703

[45] Date of Patent: ** Apr. 5, 1994

[54] TESTER FOR ENGINE SENSORS AND IGNITION MODULES

[75] Inventor: Robert A. Cervas, Highland Heights, Ohio

[73] Assignee: Actron Manufacturing Company, Cleveland, Ohio

[**] Term: 14 Years

[21] Appl. No.: 3,314

[22] Filed: Jan. 6, 1993

[52] U.S. Cl. D10/78

[58] Field of Search ..... 324/156, 158 F, 378-384; D10/78

CLAIM

The ornamental design for a tester for engine sensors and ignition modules, as shown.

DESCRIPTION

FIG. 1 is a top perspective view of the tester for engine sensors and ignition modules showing my new design; FIG. 2 is a bottom perspective view of the tester for engine sensors and ignition modules of FIG. 1; FIG. 3 is a top plan view of the tester for engine sensors and ignition modules of FIG. 1; FIG. 4 is a side view of the tester for engine sensors and ignition modules of FIG. 1; FIG. 5 is a bottom plan view of the tester for engine sensors and ignition modules of FIG. 1; FIG. 6 is a front end view of the tester for engine sensors and ignition modules of FIG. 1; and, FIG. 7 is a rear end view of the tester for engine sensors and ignition modules of FIG. 1.
